US00D768605S

(12) **United States Design Patent** (10) **Patent No.:** **US D768,605 S**
Wong et al. (45) **Date of Patent:** **** Oct. 11, 2016**

(54) **REMOTE CONTROL**

(71) Applicant: **SKY UK LIMITED**, Grant Way, Isleworth, Middlesex (GB)

(72) Inventors: **Andrew Wong**, Herrenberg (DE); **Christopher Kuh**, San Francisco, CA (US)

(73) Assignee: **SKY UK LIMITED**, Isleworth, Middlesex (GB)

(**) Term: **14 Years**

(21) Appl. No.: **29/521,038**

(22) Filed: **Mar. 19, 2015**

(30) **Foreign Application Priority Data**

Sep. 19, 2014 (EM) 001421416-001
 Sep. 19, 2014 (EM) 001421416-002

(57) **CLAIM**

The ornamental design for a remote control, as shown and described.

DESCRIPTION

FIG. 1 shows a perspective view of a first embodiment of a remote control showing my new design;

FIG. 2 shows a front elevation view thereof;

FIG. 3 shows a rear elevation view thereof;

FIG. 4 shows a right side elevation view thereof;

FIG. 5 shows a left side elevation view thereof;

FIG. 6 shows a top plan view thereof; and,

FIG. 7 shows a bottom plan view thereof.

1 Claim, 7 Drawing Sheets
